WIRE STRAIGHTENING AND TENSIONING ATTACHMENT FOR BALING MACHINE

Arthur L. Kiesow and Paul E. Rehr,
Downers Grove, Ill.

Application October 24, 1952, Serial No. 316,646

10 2 Claims. (Cl. 153—104)

This invention relates to wire straightening and tensioning devices and more particularly to such devices in the form of attachments mounted on baling machines to straighten and tension the baling wire as it is bound about the bales produced by such machines.

It is among the objects of the invention to provide an improved wire straightening and tensioning device which can be applied as an attachment to an existing baling machine to straighten and tension the baling wires as they are bound about the bales produced by the machine; which can be installed on an existing machine with no material modification of the machine construction, which are adjustable to vary the tension provided on the baling wire; which are effective to straighten without breaking or stretching the wire; and which are simple and durable in construction, economical to manufacture, and positive and effective in operation.

Other objects and advantages will become apparent from a consideration of the following description and the appended claims in conjunction with the accompanying drawings, wherein:

Figure 1 is a front elevational view of a wire straightening and tensioning device illustrative of the invention;

Figure 2 is a top plan view of the device illustrated in Figure 1 with a portion broken away and shown in cross section to better illustrate the construction of the device;

Figure 3 is a rear elevational view of the device;

Figure 4 is an end elevational view of the device with parts broken away;

Figure 5 is a transverse cross sectional view on the line 5—5 of Figure 1;

Figure 6 is a fragmentary perspective view showing the application of wire straightening and tensioning devices of the invention to a baling machine; and

Figure 7 is an elevational view of one of the journal pins of the device, a portion of the pin being broken away and shown in cross section to better illustrate the construction thereof.

With continued reference to the drawings, the wire straightening and tensioning device comprises a frame in the form of a metal plate 10 of elongated, rectangular shape having at its midlength location a transversely extending, closed slot 11 and spaced apart apertures therein at each side of the slot. Guide bars 12 and 13 extend transversely of the plate 10 one near each end of the plate and at the same side thereof and these guide bars are secured to the plate by suitable means, such as the bolts 14 and 15 for the bar 12 and the bolts 16 and 17 for the bar 13. The bolts 14 and 15 extend through registering apertures in the bar 12 and the plate 10 and are disposed one near each end of the bar and are provided with nuts bearing against the side of the plate 10 remote from the bar 12 to firmly clamp the bar to the plate. The bolts 16 and 17 extend through registering apertures in the bar 13 and the plate 10 and are disposed one near each end of the bar and provided with nuts bearing against the side of the plate 10 remote

2

from the bar 13 to firmly clamp this bar to the plate. The bar 12 is provided at its midlength location with an aperture 18 extending transversely therethrough in a direction such that the longitudinal center line of the aperture is substantially parallel to the longitudinal center line of the plate 10 and the bar 13 is provided with a similar aperture 19.

A slide block 20 of elongated, rectangular shape is disposed against the side of the plate 10 remote from the bars 12 and 13 and in overlying relationship to the slot 11 in the plate 10 and has at one end a perpendicularly projecting flange 21 overlying the adjacent edge of the plate 10. The flange 21 is provided with spaced apart, screw threaded apertures and set screws 22 and 23 are threaded through these apertures and are disposed perpendicular to and bear against the edge of the plate 10 adjacent the flange 21 to hold the slide block 20 in selected positions of adjustment transversely of the plate 10. These set screws are provided with lock nuts 24 and 25 respectively, which bear against the flange 21 of the slide block to lock the set screws in adjusted position.

The slide block 20 is provided with an aperture 26 which registers with the slot 11 in the frame plate 10 and a journal pin 27 has a screw threaded end portion 28 extending through the aperture 26. The journal pin 27 projects from the same side of the frame plate 10 as that from which the guide bars 12 and 13 project and is provided at its end remote from the screw threaded portion 28 with a head 29 of polygonal shape. Between the head 29 and the screw threaded portion 28 the journal pin has a bearing portion 30 of a diameter somewhat greater than the diameter of the end portion 28 and a roller 31 having spaced apart peripheral grooves 32 and 33 is journaled on the bearing portion 30 of the journal pin 27.

As is particularly illustrated in Figure 7, the journal pin 27 is provided in the head 29 thereof with a screw threaded well or recess 34 and in the bearing portion 30 thereof with a transversely extending lubricant passage 35 connected to the inner end of the recess 34 by a passage 36 extending longitudinally and substantially coaxially of the pin. A grease pressure fitting 37, of well known construction, is threaded into the recess 34 for supplying lubricant through the passages 36 and 35 to the bearing between the roller 31 and the bearing portion 30 of the journal pin.

The bearing portion 30 of the journal pin has a diameter somewhat greater than the width of the slot 11 and provides at the inner end of the screw threaded end portion 28 an annular shoulder which bears against the adjacent side of the plate 10 at opposite sides of the slot 11 to hold the journal pin against movement longitudinally of the frame plate and a wing nut 38 is threaded onto the screw threaded portion 28 of the journal pin and bears against the side of slide block 20 remote from frame plate 10 to clamp the slide block to the frame plate.

With this arrangement, the roller 31 can be adjustably moved transversely of the plate 10 to an extent limited by the length of the slot 11 by first loosening the wing nut 38 and then turning the set screws 22 and 23 until the slide block 20 is moved to a position transversely of the plate 10 corresponding to the desired position of the roller 31 relative to the plate. The lock nuts 24 and 25 on the set screws are then tightened to lock the set screws in adjusted position and the wing nut 38 is tightened on the journal pin 27 to firmly clamp the slide block against the frame plate.

Journal pins 40 and 41, similar in all respects to the journal pin 27, extend through apertures provided in the plate 10 at respectively opposite sides of the slot 11 and are spaced substantially equal distances from this slot and in the same direction from the longitudinal center line of the

frame plate. Nuts 42 and 43 are threaded onto the journal pins 40 and 41 at the side of the plate 10 remote from the guide bars 12 and 13 to firmly secure the journal pins to the frame plate and rollers 44 and 45 are journaled on the pins 40 and 41 respectively. Grease pressure fittings 46 and 47 are threaded into the head recesses of the journal pins 40 and 41 respectively for supplying lubricant to the bearing surface of the rollers 44 and 45, suitable bearing bushings, as indicated at 48 in Figure 2, being disposed between the several rollers and the corresponding journal pins, if desired.

The roller 44 is provided with spaced apart peripheral grooves 50 and 51 and the roller 45 is provided with spaced apart peripheral grooves 52 and 53, the grooves 51, 33 and 53 near the ends of the corresponding rollers remote from the frame plate 10 being in alignment with each other longitudinally of the frame plate.

An aperture is provided in the frame plate 10 between the guide bar 13 and adjacent end of the frame plate and between the longitudinal center line of the frame plate and the edge of the latter engaged by the set screws 22 and 23 and a journal pin 55 similar to the pins 27, 40 and 41 extends through this aperture and is clamped to the plate 10 by a nut 56 threaded onto the pin 55 at the side of the plate 10 remote from the guide bars 12 and 13. A grease pressure fitting 57 is threaded into the head recess of the pin 55 and a roller 58 is journaled on the pin 55 and provided with spaced apart, peripheral grooves 59 and 60 of which the groove 60 is in alignment with the outer grooves 51, 33 and 53 of the rollers 44, 31 and 45, the roller 58 serving as a guide roller for wire entering or leaving the device at an angle to the longitudinal center line of the plate 10.

An aperture 61 is provided in the plate 10 between the bar 13 and adjacent end of the plate and between the longitudinal center line of the plate and the edge of the plate remote from the set screws 22 and 23 and is elongated transversely of the frame plate.

A bolt 62 extends through the elongated aperture 61 for attaching the device to a suitable bracket mounted on an associated baling machine. Thus, the plate 10 carries an adjustable mounting means since the bolt 62 can be selectively positioned in the elongated aperture 61.

In using the device, the wire, as indicated at 63, is fed through the aperture in one of the guide bars 12 or 13, for example through the aperture 18 in the guide bar 12, over the roller 44 in the outer groove 51 of this roller, under the roller 31 in the outer groove 33 of this roller, over the roller 45 in the outer groove 53 of this roller, through the aperture 19 in the guide bar 13 and under the roller 58 in the outer groove 60 of this guide roller. The roller 31 is positioned relative to the rollers 44 and 45 so that the wire is bent between the rollers 44 and 45, as illustrated in Figure 1, and this bending of the wire between the rollers 44 and 45 exerts sufficient resistance to passing of the wire through the device that the wire is tensioned and pulled straight as it passes from the guide bar 12 to the bar 13. The amount of bend imposed in the wire by the straightening rollers 44, 45 and 31 is regulated by moving the roller 31 transversely of the plate pin by adjusting the slide block 20, as described above, so that any desired amount of tension can be imposed on the wire by the tensioning and straightening device.

While the device may be used with various types of wire tying baling machines, it has been especially developed for use on a hay baling machine, as fragmentarily illustrated in Figure 6. The hay baling machine as illustrated in Figure 6 has two of the above described wire straightening and tensioning devices, as indicated generally at 73 and 74, attached to the wire guide holders 80 and 81 respectively. The wire straightening and tensioning device 73 is attached at its forward end to the wire guide holder 80 by means of bolts 14 and 15 which extend through the bar 12 and plate 10 while the rearward end of the tensioning device 73 is attached to the lower end of

the bracket 75 by means of the adjustable bolt 62 extending through the slot 61 of the plate 10, the upper end of the bracket 75 being fixedly attached to the frame 82 of the hay baling machine. The wire 65 is payed out from a conventional wire holder, not shown, and is led through a tubular guide 68, thence through a guide 69 on the lower end of the bracket 87 carried by the frame 82 of the hay baling machine, thence through the wire straightening and tensioning device 73, and thence through a guide 71 carried by the wire guide holder 80.

The wire straightening and tensioning device 74 is attached at its forward end to the wire guide holder 81 by means of bolts 14' and 15' which extend through the bar 12' and the plate 10' while the rearward end of the tensioning device 74 is attached to the lower end of the bracket 76 in a like manner as that of the lower end of the bracket 75, the upper end of the bracket 76 being fixedly attached to the frame 82 of the hay baling machine. Another wire 66 is payed out from another conventional holder, not shown, and is led through a tubular guide 85, thence through a guide 86 on the lower end of a bracket 88 carried by the frame 82 of the hay baling machine, thence through the wire straightening and tensioning device 74, and thence through a guide 72 carried by the wire guide holder 81.

It has been found that the provision of these wire straightening and tensioning devices maintain the baling wires in a straight condition and under suitable tension so that the wires are bound tightly around the bales produced by the baling machine and the tying mechanism of the machine operates efficiently to tie the ends of the wires together and that broken wires, undesirable slack in the wires and faulty tying of the wires are thus substantially eliminated.

While only one peripheral groove in each roller is used at any one time, it has been found desirable to provide the rollers with more than one wire-receiving groove as wear on these rollers by the baling wire is rapid during continued and heavy use of the machine and the provision of the additional groove or grooves permits reconditioning of the mechanism by merely removing the rollers from the frame plate 10, reversing the rollers end for end and remounting them on the frame plate.

The invention may be embodied in other specific forms without departing from the spirit or essential characteristics thereof. The present embodiment is therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. In a baling machine having wire guides mounted thereon in spaced apart relationship; the improvement residing in a wire straightening and tensioning device mounted on said machine between said guides and comprising a frame plate, a plurality of rollers rotatably mounted on one side of said frame plate in spaced apart relation to each other, said frame plate having a transversely extending slot adjacent its midpoint location, a slide block carried by and extending transversely of said frame plate on the other side thereof remote from said one side for transverse sliding movement thereon in overlying relation to said slot, a journal pin carried by said block and extending through said slot, a roller rotatably mounted on said journal pin adjacent one end thereof remote from said block and disposed to said one side of said frame plate, a flange carried by said block at one end thereof and projecting laterally therefrom spaced from an adjacent edge of said plate, said flange having spaced threaded walled apertures, set screws received in each of said apertures bearing against said adjacent edge of the frame plate to hold said block in a selected position of adjustment transversely of said frame plate and to hold said roller

carried by said block at a selected position relative to said plurality of rollers, and securing means carried by said journal pin to clamp said block plate against said frame plate for maintaining said block in the selected position of adjustment.

2. In a baling machine having wire guides mounted thereon in spaced apart relationship; the improvement residing in a wire straightening and tensioning device mounted on said machine between said guides and comprising a frame plate, a plurality of rollers rotatably mounted on one side of said frame plate in spaced apart relation to each other, said frame plate having a transversely extending slot adjacent its midpoint location, a slide block carried by and extending transversely of said frame plate on the other side thereof remote from said one side for transverse sliding movement thereon in overlying relation to said slot, a journal pin carried by said block and extending through said slot, a roller rotatably mounted on said journal pin adjacent one end thereof remote from said block and disposed to said one side of said frame plate, 20 a flange carried by said block at one end thereof and projecting laterally therefrom spaced from an adjacent edge of said plate, said flange having spaced threaded walled

apertures, set screws received in each of said apertures bearing against said adjacent edge of the frame plate to hold said block in a selected position of adjustment transversely of said frame plate and to hold said roller carried by said block at a selected position relative to said plurality of rollers, and securing means carried by said journal pin to clamp said block plate against said frame plate for maintaining said block in the selected position of adjustment, said securing means carried adjacent the end 10 of said journal pin remote from the end carrying said roller.
